(57) **CLAIM**

We claim the ornamental design for the slow pitch jig, as shown and described.

DESCRIPTION

FIG. 1 is a top view of a slow pitch jig.

FIG. 2 is an enlarged front-end view of the slow pitch jig (the rear end view being identical to the front-end view).

FIG. 3 is a left-side view of the slow pitch jig (the right-side view being a mirror image of the left-side view); and,

FIG. 4 is a perspective view of the slow pitch jig.

The broken lines in the drawings illustrate portions of the slow pitch jig which form no part of the claimed design.
